UNITED STATES PATENT OFFICE.

ELLWOOD G. MACOMBER, OF PORTSMOUTH, RHODE ISLAND.

ANKLE-SUPPORT FOR SKATES.

SPECIFICATION forming part of Letters Patent No. 249,964, dated November 22, 1881.

Application filed September 29, 1881. (No model.)

To all whom it may concern:

Be it known that I, ELLWOOD G. MACOMBER, of Portsmouth, in the county of Newport and State of Rhode Island, have invented certain new and useful Improvements in Ankle-Supports for Skates, of which the following is a specification.

Reference is to be had to the accompanying drawing, forming part of this specification, which is a perspective view of my improvement, shown as applied to a skate.

The object of this invention is to provide ankle-supports for skates simpler in construction and less expensive in manufacture than those heretofore made.

The invention consists in providing the forward edge of the heel-plate of the skate with a socket, in which is secured the bent lower end of an upright rod, to the upper end of which is attached a divided leg-band, one leaf or section of which is closed by the pressure of a spiral spring that is carried on the upright rod, the degree of pressure of the spring being made adjustable, as desired.

A represents an ordinary skate, the heel-plate B of which is extended forward and is bent over upon itself until its edge nearly meets its body to form a socket, C, to receive the horizontal arm D formed by bending the lower end of the upright rod E at right angles and hinge the said upright rod to the heel-plate. The arm D passes through the socket C, and its outer end is bent forward to form a knob, F, to keep the said arm in place in the said socket C. With this construction, by swinging the upright rod E downward to turn the arm D through about a half-revolution, the knob F will be brought opposite the space between the edge of the socket C and the body 40 of the heel-plate, and can be slipped out through the said space to detach the rod E from the skate A.

The upper end, G, of the upright rod E is bent over into U form, and to it is secured, by 45 rivets or other suitable means, the end of a half-band, H.

To the upper part of the upright rod E is hinged a corresponding half-band, I, by an eye formed upon the end of the said half-band I, 50 to receive the said rod E, or by other suitable

means, so that the half-band I will be directly opposite the half-band H. The half-band I is held forward or toward the half-band H by a spiral spring, J, placed upon the upper part of the upright rod E. The upper end of the spring 55 J is attached to the hinged half-band I, and its lower end is attached to a collar, K, placed upon the upright rod E and secured in place by a set-screw, L, so that by loosening the said set-screw L the collar K can be turned upon 60 the rod E to increase or lessen the tension of the spring J, as may be desired. With this construction the divided band H I can be readily applied to and detached from the leg of the skater, and when applied will support the ankle against turning over toward either side, while allowing it to turn forward and back freely, so that the ankle will be supported against being strained.

Having thus fully described my invention, 70 I claim as new and desire to secure by Letters Patent—

1. An ankle-support for skates, constructed substantially as herein shown and described, with the forward edge of the heel-plate provided with a socket in which is secured the bent lower end of an upright rod, to the upper end of which is attached a divided leg-band, one leaf or section of which is closed by the pressure of a spiral spring that is carried on 80 the upright rod, and the degree of pressure of which is made adjustable, substantially as herein shown and described.

2. In an ankle-support for skates, the combination, with the spiral spring J and the upright rod E, carrying the stationary half-band H and the hinged half-band I, of the collar K and the set-screw L, substantially as herein shown and described, whereby the tension of the said spring can be readily regulated, as set 90 forth.

3. In an ankle-support for skates, the heel-plate B, made substantially as herein shown and described, with an open socket at its forward edge to receive the bent lower end of the 95 upright rod, as set forth.

ELLWOOD GASSETT MACOMBER.
